CLAIM

The ornamental design for an electrical apparatus with a line side isolation safety switch, as shown and described.

DESCRIPTION

FIG. 1 is a top, side perspective view of an electrical apparatus with a line side isolation safety switch showing our new design;

FIG. 2 is a front view thereof;

FIG. 3 is a back view thereof;

FIG. 4 is a side view thereof;

FIG. 5 is an opposing side view thereof;

FIG. 6 is top view thereof; and,

FIG. 7 is a bottom view thereof.

The evenly spaced dashed broken lines illustrate portions of the article which form no part of the claimed design.

1 Claim, 5 Drawing Sheets
